APPARATUS FOR HANDLING METAL STRIP

John F. Ferm, Midland, Pa., assignor to Crucible Steel Company of America, New York, N. Y., a corporation of New Jersey

Application July 10, 1941, Serial No. 401,775

13 Claims. (Cl. 266—3)

This invention relates to apparatus and equipment for controlling and regulating the travel of strip metal, and more particularly its speed and tension at various points, while the strip is being subjected to annealing or other possible treatments of a character to be applied uniformly and continuously as the strip passes through the equipment.

The continuous annealing of metal strip such as steel strip in tin plate gauges or heavier gauges, involves a number of difficulties which are overcome by this invention, as regards proper control or regulation of the strip speed and tension as it passes through the annealing furnace, as well as during its travel through other necessary portions of the equipment prior and subsequent to the furnace. The strip stock to be annealed in steel mills is ordinarily available in predetermined lengths, each wound in a coil for example on a winding block. In order to provide a continuous strip adapted for continuous feeding through annealing apparatus, it is necessary to first provide means for unwinding such coils in succession and for welding or otherwise securing the terminal ends of each length to the leading end of the next succeeding length to be fed through the apparatus. Since such welding occupies at least a brief time interval during which the travel of the strip has to be interrupted at the point of welding, provision at subsequent points in the equipment has to be made for permitting the portions of the strip being annealed to continue to travel uniformly through the annealing furnace.

Further difficulties arise in feeding or advancing the strip at the same desired adjusted speed, both to and from the annealing furnace and with uniform tension within the furnace and cooling apparatus associated therewith. That is, the motor driven means for feeding the strip to and from the furnace should preferably be adjustable to permit proper adjustment of the rate or duration of the annealing process. Also at the same time, means are not only necessary for adjusting the rate of feeding of the strip into the furnace to generally correspond to the selected speed of delivery from the furnace, but readjustments of the relative speeds into and from the furnace must be made whenever necessary to keep the tension within predetermined limits despite possible slippage or other variations in the feeding apparatus and despite variations in the stretching of the heated strip arising from minor irregularities in the stock and possible irregularities in the heating and subse-

quent cooling thereof. Otherwise the strip might at times be subjected to excessive stretching or breakage, or slack might accumulate and interfere with proper regulation of the rate of treatment or the duration of the heating and cooling steps.

After the strip has been treated and upon its delivery from the equipment, the necessary rewinding of the strip and the cutting of same into lengths for the purpose of recoiling of such lengths respectively on separate wind-up blocks, involves further difficulties. That is, the wind-up tension and any variations thereof must be counteracted and kept from altering the speed and tension of the strip as delivered from the annealing apparatus. Also since the cutting of the strip temporarily releases the wind-up tension, provision must be made for maintaining continuous and uniform withdrawal of the strip from the apparatus despite such interruptions.

In addition to the above problems, it is necessary to provide means for either stopping the apparatus or quickly correcting the speed and tension of the strip when very abnormal conditions arise, so that abnormal heating and ruination of sections of the strip may be avoided in the furnace, or at least breakage of the strip and the necessity of rethreading another strip through the equipment may be avoided.

Various further and more specific objects, features and advantages of the invention will more clearly appear from the detailed description given below taken in connection with the accompanying drawings which form a part of this specification and illustrate merely by way of example certain preferred forms of the invention. The invention consists in such novel features, arrangements and combinations of parts as may be hereinafter disclosed and claimed.

In the drawings, Fig. 1 is a somewhat schematic diagram showing as an example, a preferred arrangement of equipment embodying the invention, together with a diagram of a preferred example of electrical control circuits for the various motors of such equipment;

Figs. 2, 3 and 4 respectively are front and side elevational, and partial sectional plan views showing the mechanical parts of a preferred arrangement of automatic tension control apparatus in accordance with one example of the invention;

Figs. 5 and 6 are side elevational and plan views respectively showing one example of a preferred arrangement of the apparatus at the delivery end of the equipment;

Fig. 7 is a vertical sectional view taken substantially along the line 7-7 of Fig. 3;

Figs. 8, 9 and 10 are views taken substantially along the line 8-8 of Fig. 7, showing certain parts in three different possible positions of adjustment;

Fig. 11 is a sectional view of an adjustable friction drive mechanism which may be used according to the invention, in the example of the apparatus shown in Figs. 5 and 6, and

Fig. 12 is a somewhat schematic diagram of an alternative arrangement of the apparatus at the delivery end of the equipment.

Referring now to Fig. 1, the metal strip which is to be treated and the travel of which is to be controlled in the apparatus, is indicated at 20. This strip may be unwound from a coil carried by a pay-out block as at 21 or 22 and then passed over suitable guide rollers as at 23, through a spot welding device schematically indicated at 24, thence through a clamping device schematically indicated at 25, and then through slack take-up mechanism as somewhat schematically indicated at 26, and described in detail in my copending application filed January 30, 1941, for Patent No. 2,280,943, granted April 28, 1942, and entitled "Apparatus for handling metal strip," reference to which is hereby made. In brief, this equipment, which, per se is not herein claimed, provides an arrangement whereby when the metal strip on the pay-out block 21 for example, is all or nearly all unwound, then its end or a terminal portion thereof may be brought into contact at the welding device 24 with the leading end of another length of strip stock from another pay-out block such as at 22. Then the welding device is operated for welding the two strips together to form a continuous strip which may pass through the annealing apparatus without interruption. However, since the travel of the strip has to be temporarily halted at the welding device, the slack take-up mechanism 26 in conjunction with the clamping device 25, are arranged in such a way that portions of the strip traveling through the parts of the equipment subsequent to the take-up mechanism 26, are permitted to continue their travel at a substantially uniform rate. That is, the take-up mechanism may comprise a plurality of fixed rollers 27, over which the strip is passed alternately with rollers as at 28, which latter rollers are movable vertically on a carriage 29. Thus at some time prior to the arrival in the welding device 24, of the end of a length of the strip, the rollers 28 may be gradually moved to an elevation such as shown, to accumulate a reserve supply of the strip, in the form of loops 30, between the various rollers 27, 28. Then when the end of a length of strip stock arrives in the welding device, it is clamped by the device 25 against further travel, pending the welding thereto of the lead end of the next length of strip stock. And during this welding operation the carriage 29 may be gradually lowered so that the reserve accumulation 30 continues to supply the amount of strip necessary to maintain continuous travel of the strip through subsequent parts of the equipment. After the welding step is completed, the clamping device 25 is released and the travel of the strip continues as before, but from another pay-out block as at 22.

After leaving the take-up mechanism 26, the strip may pass between a pair of pinch rollers as at 31, one of which may be driven as through a sprocket and chain connection 32 and shaft 33

by a motor 34 having a field winding 34'. Next, the strip may be passed in the form of a loop of variable length, over a "dancer" roll as at 35 which is preceded and succeeded by suitable guide rolls as at 36. The dancer roll 35 may be supported in a counterweighted carriage 37 adapted to move up and down in a guide frame 38 in response to variations in the tension of the strip 20. Further details as to the construction and mounting of this dancer roll carriage will be apparent from a substantially similar device hereinafter described in connection with Figs. 2 to 4. In brief, the dancer roll carriage may normally be urged upwardly against the downward force of the strip on the roller by a suitable cable, pulley and counterweight arrangement. Thus, when the tension on the strip 20 tends to increase, the dancer roll carriage will be drawn downwardly, and conversely, when the strip tension tends to decrease, the dancer roll carriage will move upwardly.

The purposes of the dancer roll 35 include that of controlling certain circuits which in turn re-adjust or control the speed of the motor 34 and the consequent speed of rotation of the pinch rolls 31, upon variations in the tension of the strip. That is, an electrical contact as at 40 may be mounted on the dancer roll carriage 37 and grounded as indicated at 41. This contact upon vertical movements of the dancer roll is adapted to complete electrical circuits through various contacts as at 42 to 45 inclusive, in vertical spaced relation along the dancer roll frame. The manner in which these contacts serve to control the motor 34 will be explained hereinafter in further detail.

From the dancer roll assembly the strip 20 may travel through an annealing furnace of a suitable known type as schematically indicated at 46. Then the strip may be passed over a cooling table or chamber as somewhat schematically indicated at 47 and thence through a cooling tower similarly indicated at 48. The cooling table may include a plurality of feed rolls as at 49 connected together as by a chain drive, the latter in turn being driven as through a shaft 50 by a motor 51 having a field winding as at 51'.

From the cooling tower 48 the strip may be passed under another dancer roll as at 52, thence over a suitable swivel guide roll as at 53 and then over the rolls of a bridle stand as at 54. The dancer roll 52 as shown, may be mounted in a suitable support pivoted as at 55 and carrying a switch operating arm 56 for engaging a circuit closing switch 57. When the tension of the strip 20 at the dancer roll 52 exceeds a safe predetermined limit, this roll is elevated to thereby cause the arm 56 to close the switch 57. This in turn will cause various of the motors to stop in a manner hereinafter described.

The bridle stand rolls 54 may be driven as by a motor 58 having a field winding 58'. After leaving the bridle stand, the strip 20 may pass under another dancer roll as at 60 mounted upon a carriage slidable vertically on a frame 61, the details of construction of which are hereinafter described in connection with Figs. 2 to 4. Upon or adjacent this frame, a normally closed switch as at 62, and a normally open switch as at 63 may be mounted and arranged to be operated by suitable switch operating arms as at 64 and 65 mounted on the dancer roll carriage for vertical movement therewith. One of the purposes of the dancer roll 60 and its associated switches is to control the speed of a motor 66 having a

field winding 66', such motor serving to drive the subsequent portions of the equipment. The vertically slideable carriage for the dancer roll 60 may be in part supported by the tension of the strip 20 and further supported by a counterweight 67 connected as by a cable 68 to the dancer roll carriage, the cable running over a pulley as at 69 at the top of the frame 61. The cable 68 may also pass with one or more turns around a pulley 70 connected as by a chain drive 71 for operating a rheostat as at 72 in circuit with the motor field winding 66'.

After leaving the dancer roll 60, the strip 20 may pass to a delivery and wind-up arrangement including a plurality of pairs of pinch rolls as at 74. These rolls may be driven by friction drive means hereinafter described, permitting slippage of each roll individually in respect to chain drive means as at 75. The drive means 75 in turn may be driven as by a chain 76 connected to speed reduction drive means as at 77, the latter in turn being driven through gearing as at 78 by the motor 66. From the rolls 74 the strip may pass over a guide roll as at 79 and thence to a wind-up block as at 80 or 81. These wind-up blocks may be alternately driven by the motor 66 through suitable friction slip clutch connections at 82, 83 as hereinafter described, and driven by shaft 84 connected to the motor 66.

The strip as it is being wound on either wind-up block 80 or 81 will ordinarily be under sufficient tension so that it will over-drive pinch rollers 74, that is, cause their friction drives to slip, whereby these rolls will rotate at a speed faster than they would normally be driven by the motors 66. However, the speed of this motor as controlled by the dancer roll 60, will be regulated through circuits described below, so that sufficient friction is applied through the driving connections of rolls 74 whereby the strip is delivered from the preceding equipment at a uniform and relatively slow rate of travel and with a regulated tension from the bridle stand 54, even though the pull on the strip from the wind-up block may be excessive or variable.

The pinch rolls 74 in cooperation with the dancer roll 60 also regulate the delivery of the strip at a uniform rate of travel with a regulated tension from the bridle stand 54, even though it is necessary from time to time to cut the delivered strip in order to shift from a filled wind-up block as at 81 to an empty wind-up block as at 80 for example, or vice versa. That is, when for example the wind-up block 81 is about filled, the operator may cut the strip at a point between guide roll 79 and wind-up block 81, and then carry the severed strip end, as it is being delivered, over to the wind-up block 80 for attachment to the latter. Thereupon the clutch for wind-up block 80 may be engaged. Thereafter wind-up block 81 may be disconnected and the filled block replaced by an empty block ready for use when the block 80 is filled. During these shift-over operations, since the wind-up blocks will not apply any tension to the strip, the strip will of course be driven at the pinch rolls 74 at a speed determined by the speed of motor 66 acting through the above mentioned friction drive means on these rolls. The speed of motor 66 and its drive connections to the rolls 74 may normally be such that during this shifting from one wind-up block to the other, the rolls 74 will rotate slower than when over-driven by the tension from a wind-up block.

Accordingly at these times dancer roll 60 will be gradually lowered, thus increasing the size of the strip loop between the bridle stand 54 and rolls 74. This will of course continue to permit the strip to travel from the bridle stand 54 at substantially a uniform rate and under substantially the same tension. But since some of the strip accumulates in the loop of increasing size, the end of the strip will not be delivered from rolls 74 as rapidly as the normal strip speed and hence the operator will be given ample time to shift from one wind-up block to the other. The operator ordinarily will complete these operations before the dancer roll 60 falls to the bottom of its carriage frame. Thereupon the over-drive for the pinch rolls 74 by tension from the new wind-up block will in due course cause the dancer roll 60 to be elevated to its normal position again.

20 The operating and control circuits for the various drive motors will now be described in connection with the circuit diagrams of Fig. 1. Power may be supplied from an alternating current source to a motor-generator set 85, the generator of which has a field winding 85' connected through an adjustable rheostat as at 86 to a 220-volt D. C. source of power 87. In this way through adjustments of the rheostat 86, direct current may be furnished to power mains 88, 89, with a wide range of adjustable voltages. The armatures of the various motors 34, 51, 58 and 66 as shown may be supplied with power from the mains 88, 89 and thus the speed of these motors as a group, may be adjusted by varying the voltage across the mains 88, 89 through adjustments of the rheostat 86. The field windings as at 34', 51', 58', 66' for the various drive motors as shown may all be connected to the 220-volt source of supply 87. With the particular arrangement shown, the field winding for motor 58 which drives the bridle stand rolls 54, is connected directly across the constant voltage D. C. supply 87, whereas the fields for the other drive motors 34', 51' and 66', all have individual automatic or manual adjustments permitting the speeds of the latter motors to be individually adjusted so as to maintain the proper rate of travel of the metal strip 20 at the desired regulated tensions both to and from the bridle stand 54. That is, once the motor 58 is adjusted at its desired speed determined by the voltage across mains 88, 89 (or from any other suitable source), then the speeds of the other motors may be governed or adjusted accordingly in various ways, hereinafter described.

55 First, a single manually adjustable rheostat 90 may be provided in circuit with the field windings 34', 51' and 66', whereby motors 34, 51 and 66 may be initially manually adjusted at the proper speeds to correspond with the speed of motor 58, the latter motor in effect operating as a pilot motor. That is, as will be apparent from the diagram of Fig. 1, rheostat 90 has one end connected to the 220-volt D. C. supply 87 and its other end attached by connections 91, 92 and 93 respectively to the field windings 34', 51' and 66'.

60 As above stated, the dancer roll 35 is accompanied by circuit control means to readjust from time to time the speed of motor 34, and consequently control the tension on the strip between the first pair of pinch rolls 31, and the bridle stand 54, thus preventing undue stretching or excessive slack in the annealing furnace 48. It is important to thus regulate the tension, in view of

the heated, softened condition of the strip within the furnace. That is, any stretching of the hot strip should either be eliminated or made uniform and to this end the tension of the strip entering the furnace should preferably be regulated with substantial uniformity, and particularly any very excessive tensioning or slackening should be avoided.

One form of control circuit arrangement for the motor 34 whereby the above objects may be carried out will now be described. As shown, the connection 91 for field winding 34' may be continued through an automatically adjustable rheostat as at 94 and thence through a resistance 95 to one side of the field winding 34', the other side of which is, as shown, connected to a grounded side of the 220-volt supply 87. A reversible electric motor 96 may be provided for operating the adjustable rheostat 94 through suitable gearing as at 97. A connection 98 for driving the motor 96 in one direction, runs to switch contact 43 adjacent the dancer roll frame 38. A connection 99 for operating motor 96 in the opposite direction, runs as shown to switch contact 44 also at the dancer roll frame. The return wire 100 for motor 96 may be connected as shown to one side of the power source 87. With this arrangement the rheostat 94 may be automatically operated as follows. Assuming that the tension in the strip 20 as it enters the annealing furnace is increased, then the dancer roll 35 will be pulled down and if this tendency is somewhat abnormal, then grounded contact 40 on the dancer roll carriage will complete a circuit from ground 41, contact 40, switch contact 44, connection 99 through motor 96, connection 100 to one side of the source of power 87, the other side of which is grounded. This will cause the motor 96 to rotate in a direction tending to decrease the resistance offered by rheostat 94, thus causing motor 34 to increase progressively its speed so long as this circuit is maintained, and thereby the tension on the strip 20 as it enters the annealing furnace is lessened. When as a result of the lessening of the tension, the dancer roll 35 is raised enough to remove contact 40 from switch contact 44, then of course the circuit for motor 96 will be opened and motor 34 will continue to run at its increased speed, but without further increase. If the speed of motor 34 then is great enough so that the strip 20 eventually tends to become abnormally slack as it enters the annealing furnace, then the dancer roll 34 will rise to a point where contact 40 engages switch contact 43, thus operating motor 96 in a reverse direction, causing the resistance in rheostat 94 to be increased and hence causing the speed of motor 34 to be progressively decreased. Accordingly the tension in the strip 20 will tend to increase and thus draw the dancer 35 downwardly again, and again interrupting the circuit to motor 96. The motor 34 will then continue at the same speed until the tension of the strip again tends to become too great or too small.

Sometimes it may happen that sudden or excessive slackening of the tension in the strip 20 will tend to occur whereby the dancer roll 35 will be raised enough to permit contact 40 to engage switch contact 42. In that event, through connection 101 a circuit will be closed for energizing a relay 102 which will then open its "break" contact 103, and thus throw in series with field 34', the resistance 95, and this will quickly decrease the speed of motor 34, tending to rapidly increase the tension of the strip 20,

until contact 40 leaves switch contact 42 for again releasing relay 102. Similarly at other times the strip tension may vary excessively or suddenly tend to increase to a point where dancer roll 35 is lowered enough for contact 40 to engage switch contact 45. Then through a connection 104, a relay 105 will be energized, causing its "make" contact 106 to be closed. This in turn, by reason of connections 91 and 107, causes the resistance of rheostat 94 to be short-circuited. Hence in that case the motor 34 will rapidly increase its speed, and tend to slacken the strip tension progressively until such time as contact 40 leaves switch contact 45, whereupon relay 105 will be released and the control of motor 34 will revert to the automatically adjustable rheostat 94 and as determined by motor 96 and switch contacts 43, 44.

Thus in effect the speed of motor 34 may be controlled in four different ways, viz: (a) its speed may be initially controlled to generally correspond to that of motor 58 through adjustment of the armature voltages as determined by the voltage across the supply mains 88, 89, which is in turn controlled by the adjustable rheostat 86; (b) the speed of the three motors 34, 51 and 66, as a group, may be controlled to correspond to the speed of motor 58 by controlling the field circuits of these motors individually if preferred, or with the single manually adjustable rheostat 90; (c) the speed of motor 34 individually may be regulated automatically to regulate the tension of the strip as it enters the furnace, within relatively narrow limits by the action of the switch contacts 43, 44, motor 96 and rheostat 94, and (d) abnormal tension or slackening of the strip at this point may be corrected by the action of the switch contacts 42 and 45 acting respectively through the relays 102 and 105 to suddenly and substantially increase or decrease the resistance in the circuit of field winding 34'. It will be observed that these control arrangements collectively insure that the strip will be not only passed into the annealing furnace at the desired regulated tension, but that also the strip will be fed to and through the furnace at the proper speed to generally correspond with the speed of travel of the strip over the bridle stand 54.

The speed of motor 51 which drives the strip through the cooling chamber 47 as above indicated may be adjusted by the manual rheostat 90 in circuit with the field winding 51'. Thus the speed of the strip through the cooling chamber and cooling tower 48 may be maintained the same as at the bridle stand 54, as driven by the motor 58.

As above indicated, if the tension of the strip as it leaves the cooling tower 48 should for any reason become abnormally great, then dancer roll 52 will be elevated to close switch 57. This in turn will energize relays as at 110, 111, 112, each having "break" contacts as shown in circuit with the armature windings of motors 34, 51 and 58. Accordingly each of these motors will be stopped until the condition causing the abnormal tension at dancer roll 52 is corrected. This will prevent breakage of the strip at any point between the pay-out blocks 21, 22 and the bridle stand 54, thus avoiding the difficulties of reintroducing a broken strip through these parts of the equipment. Although stoppage of the strip within the furnace 46 may cause overheating and thus render a section of the strip de-

fective, yet the cutting out of such defective section at the wind-up blocks when operations are resumed, may be much more easily accomplished than rethreading a new length of strip through the various parts of the equipment, as necessary if breakage occurred.

It is further noted that upon stoppage of the motor 58 and the bridle stand 54 due to the action of the dancer roll 52, the motor 66 for driving the parts which advance the strip subsequent to the bridle stand, will also be quickly stopped by the action of control circuits herein-after described. Thus when dancer roll 52 closes switch 57, all of the moving parts of the system will be directly or indirectly stopped before breaking tensions occur at any point.

As above indicated, it is desirable to deliver the strip 20 from the bridle stand 54 at a regulated and generally uniform tension and to also continue such delivery through pinch rolls 74 uniformly even during the times that the operator is shifting from one wind-up block as at 80 or 81, to the other. The circuits for controlling the speed of motor 66 to meet these conditions will now be described. As above stated, the field winding 66' is in circuit with a rheostat 72, the adjustment of which is automatically controlled by the height of dancer roll 60 operating through cable 68, counterweight 67 and pulley 70. Thus, when the tension at dancer roll 60 tends to become excessive, the dancer roll will be raised, and the counterweight 67 will be lowered. This in turn by reason of the driving connections between cable 68 and the arm of rheostat 72 will cause the effective resistance in rheostat 72 to be increased, thus reducing the speed of motor 66 and relieving the excess tension in the metal strip. Thereupon the dancer roll 60 will fall, thus raising counterweight 67 and operating rheostat 72 in the opposite direction to increase the speed of motor 66 and check any undue slackening of the strip or increase its tension again if it falls below normal.

It will be noted that one side of the armature of motor 66 is connected by a wire 115 to power main 88 through a "make" contact 116 of a relay 117. This relay is normally energized when the equipment is running and is kept energized by a "lock-up" circuit running from the grounded side of the 220-volt D. C. supply 87 through a connection 118, a "make" contact 119 on relay 117, a connection 120 running to normally closed switch 62 near the top of the dancer roll frame 61, thence this circuit runs through a connection 121 and the winding of relay 117 back to the other side of the 220-volt supply 87. However, if the tension in the metal strip at dancer roll 60 tends to become very abnormally great, either because of emergency stoppage of motors 34, 51 and 58 as above referred to, or for any other reason, then the dancer roll will be elevated to a point where switch operating member 64 mounted on the dancer roll carriage will act to open switch 62 and thus release the "lock-up" circuit of relay 117. Thus the "make" contacts 116 and 119 of this relay will be opened and the motor 66 will be stopped because of the breaking of its armature circuit. If the other drive motors continue operating, the strip will continue to be fed from the bridle stand 54 and consequently the tension at dancer roll 60 will be quickly relieved, and within a relatively short time this dancer roll will be permitted to fall far enough so that a substantial loop in the strip will accumulate at this point and finally

the switch operating member 65 on the dancer roll carriage will engage and close switch 63. From the connections shown in Fig. 1, it will be apparent that upon closing switch 63 (switch 62 being in its normally closed position), a circuit will be provided through connections 118 and 118' and switches 63, 62, for reenergizing relay 117, thus closing its two "make" contacts and again starting the motor 66 and closing the "lock-up" circuit for the relay. Thereupon the motor 66 will resume the driving of the pinch rollers 74. Since at this moment the dancer roll 60 is in its lowermost position and the counterweight 67 is in a high position, the resistance of rheostat 72 will be cut out. Consequently the motor 66 will quickly reach a speed sufficient to reduce the strip loop at dancer roll 60 to normal proportions. At the same time the rheostat 72 will be gradually readjusted so as to reduce the motor speed again to normal. Also upon the consequent raising of the dancer roll 60, the switch 63 will be restored to its normal open condition.

From the above description it will be apparent that motor 66 is controlled in four ways, viz: (a) its speed may be initially adjusted together with that of all the other motors, depending upon the rate of annealing required, by adjustment of the armature voltage, i. e., as determined by the manually adjustable rheostat 86; (b) its speed with that of motors 34 and 51 may be initially adjusted to correspond to the speed of motor 58, i. e., by manually adjustable field rheostat 90, thus giving a generally uniform rate of travel for the strip through the entire equipment; (c) the speed of motor 66 is closely regulated to regulate the strip tension between the bridle stand 54 and the delivery pinch rolls 74, by the action of the dancer roll 60 in conjunction with the field rheostat 72; and (d) the motor 66 may be automatically stopped upon very excessive tension at the dancer roll 60, and after sufficient time has elapsed to substantially reduce this tension by the accumulation of a loop at the dancer roll, then the motor is automatically started again, first at a relatively high speed, which speed is gradually diminished and regulated as the dancer roll assumes its regulating positions.

Thus the various motors and controls therefor, both prior and subsequent to the bridle stand 54, are such as to provide the necessary regulated tensions and generally uniform speeds of travel of the strip, which will permit the equipment to be continuously operated with automatic correction of all of the abnormal conditions liable to be encountered due to changes in the strip tension or minor differences of speed at various points. At the same time the various regulating devices and controls are such as to permit the operator to shift the pay-out blocks as well as the wind-up blocks when necessary without interrupting or interfering with the continuous operation of the equipment.

Further details of construction of the carriage and frame mechanism for the dancer roll 60 will now be described in connection with Figs. 2, 3 and 4. A substantially similar carriage and frame mechanism may be provided for the dancer roll 35, although it will be apparent from Fig. 1 that the latter roll in the example shown is to be counterweighted so as to form normally an upwardly extending loop whereas the dancer roll 60 forms a downward loop.

As shown, the dancer roll 60 may be mounted upon a shaft journaled as at 125 and 126 in a

carriage 127. This carriage may be provided at each side respectively with pairs of rollers as at 128, 129 adapted, together with the edges of the carriage, to embrace the edges of guide strips as at 130, 131, these strips in turn being suitably fixed to I-beams as at 132, 133, forming the sides of the frame 61 above mentioned in the description of Fig. 1. Suitable stops as at 134 may be fixed to these beams near their lower portions for limiting downward movement of the carriage 127. The various electrical contacts and switch parts may be suitably secured to the dancer roll carriages and frames at desired points determined by trial and as generally indicated in Fig. 1, for both of the dancer rolls 35 and 60. The carriage 127 is shown suspended by the cable 68 running over pulleys as at 135 and 69 mounted at the top of the frame 61 and thence down to the pulley 70. As shown in Figs. 2, 4 and 7, the pulley 70 may be formed with a spiral groove as at 136 adapted to receive a number of turns of the cable 68 and to firmly secure same against slippage. The cable runs from this pulley down to the counterweight 67.

As shown in Figs. 2 and 4 and in further detail in Fig. 7, the pulley 70 may be carried upon a shaft 137 journaled in suitable bearings as at 138, 139 mounted at the base of frame 61. The end of this shaft opposite from the pulley 70 may have affixed thereon a suitable collar member 140 formed with a lug 141, which in turn may have detachably bolted thereto a member 142 for engaging either of two plate members 143, 144 (Figs. 8-10). The plate members 143, 144 may be secured as by screw bolts as at 145 to a sprocket member 146 rotatably mounted upon shaft 137. As shown in Fig. 5, the sprocket 146 may be connected as by chain 71 to operate the rheostat 72 above mentioned in connection with Fig. 1 for controlling motor 66.

By reference to Figs. 7 and 8 it will be noted that the plate members 143, 144 in cooperation with the member 142 provide a lost motion connection as between the shaft 137 and sprocket 146. That is, after the cable has turned the pulley 70 in one direction, then if the direction of movement of the cable is reversed, the pulley 70 will turn through a considerable angle before the sprocket 146 and the rheostat 72 are operated. Thus any minor variations in the height of the dancer roll 60 which are insufficient to necessitate any change of speed for the motor 66, will not cause the rheostat 72 to be readjusted, at least until such variations accumulate or increase to a point sufficient to move the rheostat through this lost motion connection. As shown in Figs. 8-10, the amount of lost motion at this connection may be properly adjusted as determined by trial, through changing in various ways the positions of the plates 143, 144. That is, for example an annular series of 8 bolt holes may be provided in the sprocket 146 for the screw bolts 145 and this will permit these plates to be bolted on in any of the three different positions shown in these figures to provide lost motion as between the shaft 137 and the sprocket of approximately 180°, 90° or 60°.

As shown in Figs. 5 and 6, the lowermost roll as at 148 of the bridle stand 54 may be driven by connection to the motor 66. The strip 20 as shown may first pass between the two lowermost bridle stand rolls 148, 149 and then around one of the upper rolls 150 and between same and another smaller upper roll 151, and thence on to dancer roll 60. Suitable screw-down means of

known type, as at 152, may be provided for adjusting the pressure applied to the bridle stand rolls.

As further shown in Figs. 5 and 6, the delivery rolls 74 may comprise three pairs of pinch rolls between which the strip 20 passes in succession after leaving the dancer roll 60, and before passing over the final guide roll 79. Pressure on these pinch rolls may be adjusted by screw-down means of a suitable known type as at 153, including hand wheels and suitable levers as shown for operating same if desired. The driving connections 75 to 78 inclusive to the motor 66 as above mentioned in connection with Fig. 1, are shown in further detail in Figs. 5 and 6. That is, the motor shaft 84 as more clearly appears in Fig. 6 may be connected by the gears 78 to a transverse shaft 154 having sprocket chain connection 71 with a larger sprocket 155 mounted on a shaft 155'. The latter shaft may drive the sprocket and chain connection 76 to the first of the pairs of pinch rolls 74.

As indicated in Fig. 6 and as shown in further detail in Fig. 11, the lowermost of each pair of pinch rolls 74 may be each connected to a pair of sprockets as at 156, 157 through a slip-friction drive permitting these rolls to be "over-driven" by the strip tension caused by the wind-up blocks, as above explained in connection with Fig. 1. That is, these sprockets may be bolted to an annular member as at 158, the inner surfaces of which may be engaged by arcuately shaped members as at 159, 160 of angular cross section and formed with various grooves as at 161 for receiving lubricating material. This assembly of parts may be rotated upon a hollow member 162, forming an oil reservoir and having a flange 163 against which the members 160 are adapted to be pressed with adjustable pressure applied as by a hand wheel 164 acting through springs as at 165 received in annular shoes as at 166, 167 interposed between the hand wheel and the members 159. Thus the sprockets 156, 157 are connected to member 162 by a frictional drive permitting slippage at members 159, 160 to an extent depending upon the adjustment of the hand wheel 164. As shown, the collars as at 162 may be keyed to the shafts of the lowermost pinch rolls 74. The sprockets 156, 157 for the several sets of pinch rolls may all be connected and driven together by the chain 75.

It will be apparent that this type of drive for the pinch rolls 74, by counteracting the tension applied to the strip by the wind-up blocks, will serve to cause sufficient tension in the metal strip 20 at each pair of the pinch rolls to keep the strip taut between each pair of rolls and also between the first pair and the dancer roll 60. Yet if the wind-up tension tends to drive the rolls 74 too fast, the loop at dancer roll 60 will diminish and cause the motor 66 to run slower, increasing the frictional drag on rolls 74, also decreasing the speed of the wind-up blocks, hence allowing the loop to increase again. Thus the amount of tension will be so regulated by the motor 66 and its control means acting in conjunction with the dancer roll as to normally maintain a substantially uniform tension in the strip as delivered by the bridle roll stand. On the other hand, when the metal strip 20 is being cut, in order to shift from one wind-up block to another, there will be of course little or no tension in the strip subsequent to the last pair of pinch rolls 74. Yet at these times also the drive arrangement for the motor 66 acting in conjunction with its control

circuits and the dancer roll 60 as above explained with Fig. 1, will still continue to regulate the strip tension with substantial uniformity as it leaves the bridle stand, but deliver the strip more slowly from rolls 74, giving the operation ample time to shift wind-up blocks. Thus the action of the bridle stand in uniformly pulling the strip through the annealing apparatus, is not interfered with by the cutting and wind-up operations.

The above described arrangement of pinch rolls 74 is particularly adaptable for obtaining proper wind-up tension on the wind-up blocks without danger of breakage of the strip when of heavy gauge. For handling strip of tin plate gauges at the discharge end of the equipment, the arrangement diagrammatically shown in Fig. 12 may sometimes be preferred for preventing any tendency of the strip to slip on the rolls. That is, as shown in Fig. 12 such slippage may be prevented by using a horizontally arranged bridle stand as at 119 wherein the strip after passing over guide roll 171, is wrapped through a considerable arc around three successive rolls, thus preventing slippage. The three larger rolls of the assembly 170 may be driven in the same manner as rolls 74. However, when heavy gauge stock is being handled, in order to avoid substantial bending of the stock during its delivery, the arrangement of pinch rolls 74 in Figs. 5 and 6 may be preferred.

Figs. 5 and 6 also illustrate in further detail driving means for the wind-up blocks 80, 81. That is, the shaft 84 from motor 66, may be extended and connected as by gearing at 172, 173 to one side of the clutch members 82, 83 respectively, the other side of such clutch members being connected to the shafts carrying the wind-up blocks 80, 81 respectively, as will be readily understood. It will be further understood that the clutches 82, 83 are adapted to be thrown into and out of engagement alternatively, depending upon which of the winding blocks 80 or 81 is in use, and furthermore, that in view of the gradually increasing size of the coils of strip as wound on these blocks, the clutches 82, 83 are made of a suitable known type providing for increased slippage of the drive as the coils become larger, and so that the wind-up tension applied to the strip continues approximately uniform.

While the invention has been described in detail with respect to particular preferred examples, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

1. Apparatus for passing strip metal at substantially constant speed with regulated tension, through an annealing furnace and associated cooling means, comprising: motor driven pinch rolls engaging the strip in advance of the furnace, means for continuously supplying to said rolls a continuous strip of the stock to be annealed; motor driven rolls engaging the strip to pull same from the cooling means, means for initially adjusting with respect to each other the speeds of the motors for the driven rolls to cause the strip to normally travel at substantially the same speed at each set of driven rolls, a dancer roll over which the strip forms a var-

iable loop at a point between said pinch rolls and the furnace, the changes in size of such loop and the consequent position of the dancer roll depending upon variations in the length of strip between the two sets of rolls, a motor-driven rheostat connected to control the pinch roll motor speed, and control means and circuits for the rheostat motor, constructed and arranged under control of the dancer roll to operate the rheostat in a direction to decrease or increase the pinch roll motor speed respectively during times when the loop is abnormally large or small.

2. Apparatus for passing strip metal at substantially constant speed with regulated tension, through an annealing furnace and associated cooling means, comprising: motor driven pinch rolls engaging the strip in advance of the furnace, means for continuously supplying to said rolls a continuous strip of the stock to be annealed, motor driven rolls engaging the strip to pull same from the cooling means, means for initially adjusting with respect to each other the speeds of the motors for the driven rolls to cause the strip to normally travel at substantially the same speed at each set of driven rolls, a dancer roll over which the strip forms a variable loop at a point adjacent the furnace, the changes in size of such loop and the consequent position of the dancer roll depending upon variations in the length of strip between the two sets of rolls, a motor-driven rheostat connected to control the pinch roll motor speed, and control means and circuits for the rheostat motor, constructed and arranged under control of the dancer roll to operate the rheostat in a direction to decrease or increase the pinch roll motor speed respectively during times when the loop is abnormally large or small.

3. Apparatus for passing strip metal at substantially constant speed with regulated tension, through an annealing furnace and associated cooling means, comprising: motor driven sets of rolls preceding and succeeding the furnace and cooling means for advancing the strip into same and out thereof at generally the same constant speed, a dancer roll over which the strip forms a variable loop adjacent the furnace, the changes in size of such loop and the consequent position of the dancer roll depending upon variations in the relative speeds of the rolls and the length of strip between said sets of rolls, and electrical control means actuated by the dancer roll during times when the loop is abnormally large or small, and constructed and arranged for continuing to alter during said times, the relative motor speeds for said sets of rolls in a direction tending to restore the loop size to normal.

4. Apparatus for passing strip metal at substantially constant speed with regulated tension, through an annealing furnace and associated cooling means, comprising: motor driven sets of rolls preceding and succeeding the furnace and cooling means for advancing the strip into same and out thereof at generally the same constant speed, a dancer roll over which the strip forms a variable loop adjacent the furnace, the changes in size of such loop and the consequent position of the dancer roll depending upon variations in the relative speeds of the rolls and the length of strip between said sets of rolls, electrical control means actuated by the dancer roll when the loop becomes abnormally large or small, to gradually alter the relative motor speeds for said sets of rolls in a direction tending to restore the loop size to normal, and means supplementing

said control means for abruptly and substantially altering said relative motor speeds in such direction, when the dancer roll departs greatly from its normal position.

5. Apparatus for controlling the travel of metal strip through an annealing furnace, comprising: means for continuously feeding the strip into said furnace, additional means for continuously pulling the strip from said furnace, motors for respectively driving said means, means common to said motors for concurrently adjusting the speeds thereof, means for adjusting the speed of one of said motors with respect to the other for causing the strip to travel to and from the furnace at generally the same speed, and additional means controlled by changes in the length of strip between said feeding and pulling means for automatically readjusting the relative speeds of said motors when the strip speeds at said feeding and pulling means differ substantially, whereby such readjustments tend to maintain said strip speeds the same and constant within a predetermined limited range.

6. Apparatus for passing strip metal at substantially constant speed with regulated tension, through an annealing furnace, comprising means for successively removing lengths of strip stock respectively from pay-out blocks and for welding said lengths end-to-end, means for feeding the resulting continuous strip into the furnace, continuously at substantially uniform speed and under substantially a predetermined regulated tension, discharge rolls and motor driven wind-up blocks so constructed and arranged that the treated strip may be severed into lengths and coiled as discharged onto said wind-up blocks respectively, means for pulling the strip from the furnace substantially at said uniform speed, a take-up device for normally maintaining the strip taut and under constant tension between said latter means and said discharge rolls, and electrical control means actuated by said device for regulating the wind-up block motor speed.

7. Apparatus for controlling the travel of strip metal passing through an annealing furnace, comprising means for continuously feeding the strip stock into said furnace, discharge rolls and motor driven wind-up blocks so constructed and arranged that the treated strip may be severed into lengths and coiled as discharged onto said wind-up blocks respectively, means for pulling the strip from the furnace substantially at uniform speed, a take-up device for normally maintaining the strip taut and under constant tension between said latter means and said discharge rolls, and electrical control means actuated by said device for regulating the wind-up block motor speed.

8. In combination, apparatus for treating a continuous traveling metal strip, through which apparatus the strip is advanced at substantially uniform speed and regulated tension, a plurality of motor driven wind-up blocks so constructed and arranged that a length of the treated strip may be wound under tension on one block, then severed and the next length similarly wound on another block, motor driven rolls engaging the strip between said apparatus and the wind-up blocks, and means controlled by changes in the strip tension between said rolls and said apparatus for so regulating the speed of the motor drive for said rolls as to maintain said last mentioned tension approximately constant during

the operations of winding and severing of the strip.

9. In combination, apparatus for treating a continuous traveling metal strip, through which apparatus the strip is advanced at substantially uniform speed and regulated tension, a plurality of motor driven wind-up blocks so constructed and arranged that a length of the treated strip may be wound under tension on one block, then severed and the next length similarly wound on another block, a plurality of motor driven pinch rolls engaging the strip between said apparatus and the wind-up blocks, frictional slip connecting means through which said rolls are driven, and means controlled by changes in the tension of the strip between said apparatus and said rolls for so regulating the speed of the motor drive for said rolls as to maintain said last mentioned tension approximately constant during the operations of winding and severing of the strip.

10. In combination, apparatus for treating a continuous traveling metal strip, through which apparatus the strip is advanced at substantially uniform speed and regulated tension, a plurality of motor driven wind-up blocks so constructed and arranged that a length of the treated strip may be wound under tension on one block, then severed and the next length similarly wound on another block, a motor driven bridle stand between said apparatus and the wind-up blocks, the strip being bent in its travel around rolls of said bridle stand for engagement by such rolls without substantial slippage, and means controlled by changes in the strip tension between said bridle stand and said apparatus for so regulating the speed of the motor drive for said bridle stand as to maintain said last mentioned tension approximately constant during the operations of winding and severing of the strip.

11. In combination, apparatus for treating a continuous traveling metal strip, through which apparatus the strip is advanced at substantially uniform speed, a plurality of motor driven wind-up blocks so constructed and arranged that a length of the treated strip may be wound under tension on one block, then severed and the next length similarly wound on another block, a plurality of rolls engaging the strip between said apparatus and the wind-up blocks, a motor driven frictional slip connecting means for driving said rolls to continue delivery of the strip during the operations of shifting from one wind-up block to another, said rolls being normally overdriven by the strip when the strip is being pulled under tension by the wind-up blocks, with consequent application of a retarding force to the rolls through said frictional means, and means controlled by variations in the strip tension between said rolls and said apparatus for so regulating the speed of the motor drive for said rolls as to maintain said last mentioned tension approximately constant during the winding and severing operations.

12. In combination, apparatus for treating a continuous traveling metal strip, through which apparatus the strip is advanced at substantially uniform speed, a plurality of motor driven wind-up blocks so constructed and arranged that a length of the treated strip may be wound under tension on one block, then severed and the next length similarly wound on another block, a plurality of rolls engaging the strip between said apparatus and the wind-up blocks, a motor driven frictional slip connecting means for driving said rolls to continue delivery of the strip during the

operations of shifting from one wind-up block to another, said rolls being normally overdriven by the strip when the strip is being pulled under tension by the wind-up blocks, with consequent application of a retarding force to the rolls through said frictional means, and means at a point between said rolls and said apparatus for progressively accumulating some of the strip during said shifting operations while maintaining an approximately constant strip tension at such point.

13. Apparatus for controlling the travel of strip metal passing through and from an annealing furnace, comprising: means for continuously feeding the strip stock into said furnace, motor-driven discharge rolls and motor-driven wind-up blocks so constructed and arranged that the treated strip may be severed into lengths and coiled as discharged onto said wind-up blocks respectively, means for normally pulling the strip from the furnace substantially at uniform speed

5 and continuously delivering same at substantially a predetermined regulated tension to said discharge rolls, said latter means including a dancer roll around which the strip forms a variable loop at the intake side of said discharge rolls, a rheostat operatively connected and arranged with respect to said dancer roll, for regulating the motor speed for said discharge rolls and to thereby regulate the length of said loop, a pair of switches constructed and arranged with respect to said dancer roll to be operated thereby respectively upon abnormal changes in the length of said loop, and circuit means under the control of said switches for stopping the discharge roll motor 15 upon actuation of one of said switches responsive to an abnormal decrease in the length of said loop, and for starting said motor again upon actuation of the other of said switches responsive to a substantial increase in the length of said loop.

JOHN F. FERM.
